(57) **CLAIM**

The ornamental design for a personal three-wheeled vehicle, as shown and described.

DESCRIPTION

FIG. 1 is a top, front, and left side perspective view of a personal three-wheeled vehicle showing my new design;
FIG. 2 is a front elevation view thereof;
FIG. 3 is a rear elevation view thereof;
FIG. 4 is a right side elevation view thereof;
FIG. 5 is a left side elevation view thereof; and,
FIG. 6 is a top plan view thereof.

The broken lines in the drawings illustrate portions of the personal three-wheeled vehicle that forms no part of the claimed design.
